Attorney

UNITED STATES PATENT OFFICE.

THOMAS J. O'DAY, OF MALONE, NEW YORK.

SUPPORT FOR LOCOMOTIVE AIR-RESERVOIRS.

1,193,480.

Specification of Letters Patent. Patented Aug. 1, 1916.

Application filed February 12, 1916. Serial No. 77,974.

To all whom it may concern:

Be it known that I, THOMAS J. O'DAY, a citizen of the United States, residing at Malone, in the county of Franklin and State of New York, have invented certain new and useful Improvements in Supports for Locomotive Air-Reservoirs, of which the following is a specification.

This invention relates to supports and 10 more particularly to new and useful improvements in supports for locomotive air reservoirs.

An object of my invention is to provide primarily means for handling the main air 15 reservoirs employed on locomotives, whereby the reservoir may be supported at an angle and rotated for testing purposes, whereby all of the surface of the reservoir 20 may be exposed to view.

25 My invention particularly contemplates the provision of means for obviating the cumbersome, inefficient, and very often dangerous devices and means now employed in locomotive shop practice.

30 A further object of my invention is to provide a support of the class described which is adapted for a wide scope of uses, its adaptation to the use hereinafter set forth in detail being merely one of its many 35 applications:

Other objects and advantages will appear from the following detail description taken 40 in connection with an inspection of the accompanying drawings, in which—

35 Figure 1 is an end elevational view of my improved support in use, the running board and portion of a locomotive boiler being shown. Fig. 2 is a side elevational view of the same. Fig. 3 is a vertical sectional view 45 taken on the line 3—3 of Fig. 2 looking in the direction of the arrow.

Referring more particularly to the drawings, wherein similar reference characters 50 designate like and corresponding parts throughout the respective views, 1 designates a portion of a locomotive boiler from which extends the back 2 supporting the usual running board 3.

The air reservoir is designated 4, and in 55 the later types of steam locomotives is located beneath the running board on the right hand side about midway the length of the engine. In the locomotive shops at the present time, it is customary to test reservoirs at certain fixed intervals of time, the party inspecting the reservoir applying

what is known as the hammer test to the outer surface of the reservoir. In testing these reservoirs, it is necessary that the same be slightly lowered from their fastenings and rotated in order that each and every plate and the total surface of the reservoir may be reached by the hammer. At the present time, either a scaffold must be built up to the running board to support the reservoir during the testing process or cumbersome chains wrapped about the reservoir for suspending the same during said process. Very often these chains do not hold and the reservoir will slip from proper 70 position and fall to the ground or floor of the shop often injuring the reservoir or the party testing the same.

It is a primary object of my invention as hereinbefore set forth to overcome the dangers arising from the practice now existing in locomotive shops in this particular line of work, and in order to properly support a reservoir during said process of testing, I provide a pair of U-shaped cradles or 80 hangers designated 5 and 6 in their entireties. These cradles are substantially identical in form and construction and the description of one will therefore suffice.

Referring to the cradle 6, it will be noted 85 that the same is formed of two straps designated 7 and 8, said straps being substantially U-shaped in configuration and arranged in parallel spaced relation, transverse rods 9 serving to maintain said straps 90 in the position shown. A pair of adjusting and supporting members, preferably bolts 10 and 11 are pivotally connected on pins 12 to the free ends of said straps and therebetween as best shown in Fig. 2. The upper 95 ends of the bolts 10 and 11 pass through a transverse supporting bar 13 having a pair of elongated openings 14 therein adjacent its extremities, and nuts 15 are receivable on said bolts to adjust the same. The supporting bars 13 raised upon the upper surface of the running board and the bolts 10 and 11 extend outwardly on each side of 100 said running board. In order to rotatably support an object held by the cradles, I provide a plurality of revolvably mounted wheels 16, said wheels being carried by transverse pins 17 extending between the straps 7 and 8. The wheels are so positioned 105 that their respective peripheries project 110 slightly beyond the inner marginal edges of the straps 7 and 8 whereby to receive an ob-

ject, in this instance the reservoir, and revolubly mount the same. As shown to advantage in Fig. 2 the wheels are preferably provided with grooved peripheries, whereby the same will more easily accommodate themselves to the rivets 18 of the reservoir 4 when the latter is rotated.

In use, the cradles 5 and 6 are placed beneath the air reservoir and the bolts 10 and 11 are engaged by means of the nuts 15 with the transverse bars 13. Of course, any number of the cradles may be provided, but I have found that in actual practice a pair of cradles perform efficiently. The air reservoir may now be released from the permanent fastenings and supported by means of the cradles. By releasing the bolts of one of the cradles and taking up on the bolts of the other of the cradles, the reservoir 15 may be disposed at any desired angle within certain limits to be determined by the length of the bolts. In this position the reservoir may be subjected to the full air pressure and by slightly rotating the same on the wheels 20 may be hammer-tested. When the reservoir is disposed in inclined position as best shown in Fig. 2, the same will have a tendency to move forwardly as it is rotated, thereby permitting access to that portion of the reservoir adjacent the cradles—this being impossible in the devices now in use.

From the above description taken in connection with the accompanying drawings, it is thought that a clear and comprehensive understanding of the construction, operation and advantages of my invention may be had, and while I have shown and described

my invention as embodying a specific structure, I desire that it be understood that I 40 may make such changes on said structure as do not depart from the spirit and scope of the invention as described.

What I claim as my invention and desire to secure by Letters Patent is:

1. In a device of the class described, in combination with a platform, a plurality of cradles, supporting members pivotally connected therewith and extending on each side of said platform, means bearing upon the 50 upper surface of the platform and adjustably associated with said supporting members for the purpose set forth.

2. A supporting cradle, including a pair of spaced U-shaped straps having anti-friction rollers interposed therebetween, bolts pivoted between said straps at the free ends thereof, a transverse supporting bar associated with said bolts, and nuts on the free ends of said bolts for retaining the latter 60 in engagement with said bar.

3. In a device of the class described, a cradle comprising a pair of straps substantially U-shaped in configuration and arranged in spaced relation, anti-friction rollers mounted between said spaced straps to revolubly support a cylindrical object, suspending arms pivotally associated with said cradle between the free ends of the spaced straps, and a transverse bar engageable with 70 the free end of the said arm and adapted to rest upon a supporting object for the purpose set forth.

In testimony whereof I affix my signature.

THOMAS J. O'DAY.
